UNITED STATES PATENT OFFICE.

MICHAEL CAREY, OF KALAMAZOO, MICHIGAN.

CALENDAR.

SPECIFICATION forming part of Letters Patent No. 337,478, dated March 9, 1886.

Application filed November 2, 1885. Serial No. 181,552. (No model.)

To all whom it may concern:

Be it known that I, MICHAEL CAREY, a subject of the Queen of Great Britain, residing at Kalamazoo, county of Kalamazoo, State of Michigan, have invented a new and useful 5 Calendar, of which the following is a specification.

This invention has for its object the construction of an improved calendar, the details 10 of construction and the novelty being below described and claimed.

In the drawings forming a part of this specification, Figure 1 shows the calendar device complete as it appears ready for use. Figs. 2 15 and 3 are plans of the charts used in the calendar and containing subdivisions of days and years, and Fig. 4 is an edge view of Fig. 1 with charts removed.

Referring to the letters of reference marked 20 on the drawings, B is a case designed for hanging on the wall in the ordinary manner of using calendars. The face of this case bears characters subdividing the year into the number of each day in each month. At the top 25 is an opening in the form of an inverted letter T, (shown at P,) and at "a" in the month of February is another opening, the uses of which openings are below described.

In Fig. 2, D is a chart bearing characters 30 representing years in an increasing ratio, commencing with 1885, and other characters representing the days of the week. These characters (shown on the upper half of the chart) may be continued toward the right end of the 35 chart indefinitely, according to the length of the chart. That the chart may not be unduly long, I have shown such a continuation on the lower half. To use this continuation, of course the card would be inverted and operated in 40 the manner of operating it prior to inversion, as follows:

The chart D is inserted in the upper recess, R, of the case B, and adjusted so that the desired year is presented at the vertical part of 45 the opening P. In the horizontal part of this opening characters representing fourteen days are presented, which are so arranged in relation to the year, the dates of the months, and the construction of the case that the actual 50 day the year came in on will be represented by a proper character over the vertical column, in which figure "1" appears in January, and

the other days will be over the proper columns of the dates of the several months. To illustrate, take the year 1885, which is presented 55 in Fig. 1 at the year-opening. We find that this year came in on Thursday, because we find "TH." over the column containing "1" in "Jan." In like manner the other dates and days for the whole year may be traced. To 60 illustrate, take the 22d of October, pointed out by the pointer c. We find this is Thursday of the week in the year 1885—thus: "Thursday, October 22, 1885."

The dates in a receding ratio for the year 55 and their days are as readily found as those of time not yet transpired. By sliding the chart D toward the left, presenting "1886" at the year-opening, we find that the 1st day of January, 1886, would come on Friday, the 70 days in the days-opening having been moved one column. Thus the days as now adjusted and the dates of the months are in proper relation for the year 1886, as they would be for any and all years to come and for any and all past 75 years which were presented at the year-opening of the case. The exception to this which is caused by leap-years is provided for by marking "29" on the chart D at the proper position to be presented at the opening a when a given 80 leap-year is presented at the year-opening. To illustrate, if the year "1888" be presented at the year-opening, the lower left-hand "29" on the chart will be presented at the opening a, when the calendar would indicate that the 29th 85 day of February, 1888, comes on Wednesday, as "WE." would then be over the column in which 29th of February appears. The calendar is right then for January and February. The year 1888 is repeated on the chart for the last 90 ten months of the year, and to find dates for said ten months the chart is moved, presenting "1888, last 10 month," at the year-opening. This brings "TH." over the first column of month-dates, in which "1" in March appears. 95 As February 29 comes on Wednesday, of course March 1 would be on Thursday; hence it is necessary that "TH." be over the column in which March 1 appears. A like arrangement for leap-years is repeated on the chart every 100 four years.

The letters A B C, &c., in the months on the case B are for convenience in knowing which day of the week a certain date is on.

To illustrate, over the column in which October 22 appears we find L. Looking for L at the top of the calendar, we find Thursday is indicated. Thus October 22 comes on Thursday. This plan will be found more useful for other years, for the reason that in the arrangement for 1885 Sunday is in the first column of the month, Monday in the second, and so on, with Saturday in the last; but take 1886, 5 10 Friday would then be in the fifth column, and hence the letter L over October 22 would indicate Friday for 1886.

In Fig. 3 a chart, D', is shown, of like arrangement to the chart D, except the years 15 are placed in a decreasing ratio, for the purpose of finding days and dates of past years. This chart is used by taking the chart D out of its recess and inserting the former in lieu thereof. 20 For convenience in holding the chart not in use, it is inserted in the lower recess, R, of the case.

To find prior dates, suppose "1858" be presented at the year-opening of the case, we 25 would find that January 1 came on Friday of that year, because "FR." would be over the column in which 1 of January appears.

The pointer c is so fulerumed to the case at 30 that it may be swung laterally and adjusted vertically, so as to set the point at any date to readily catch the eye. Thus it can be set every night to point out the next day.

I have termed the part B a "case," because

it has a front and rear inclosure, with recesses between for containing the charts; but, so far 35 as the invention is concerned, the front calendar-card may have the chart otherwise movably connected with it, and this card may be a plate of suitable material.

Having thus described my invention, what 40 I claim as new, and desire to secure by Letters Patent, is—

A calendar consisting of a card or plate bearing associations of columns of dates representing months of the year, and having openings through the plate, one for the year, one for the days, and one in the month of February for the date 29, and a chart movable back of said openings and bearing characters in duplicate (representing a leap year) for the first 50 two months and the last ten months, the figures 29, and characters representing days, all so arranged in relation to each other, to the openings, and to the date-columns of the months that the proper days will be presented 55 over the proper date-columns for a given leap-year presented at the year-opening, and that 29 will be presented at the date-opening in the month of February, substantially as set forth.

In testimony of the foregoing I have here- 60 unto subscribed my name in presence of two witnesses.

MICHAEL CAREY.
